(57) CLAIM

The ornamental design for a colorimeter, as shown.

DESCRIPTION

FIG. 1 is a side elevation from one side of the colorimeter showing our new design;

FIG. 2 is an end elevation from one end of the colorimeter; FIG. 3 is a side elevation from the opposite side of the colorimeter;

FIG. 4 is an end elevation from the opposite end of the colorimeter;

FIG. 5 is a top plan view of the colorimeter;

FIG. 6 is a bottom plan view of the colorimeter;

FIG. 7 is a side elevation corresponding to FIG. 3 but with a battery door shown open;

FIG. 8 is a front perspective view from above and one side of the colorimeter; and,

FIG. 9 is a rear perspective view of the colorimeter from below and the other side.
